(57) **CLAIM**

I claim the ornamental design for a pen tip for touch pen, as shown and described.

DESCRIPTION

FIG. 1 is a perspective view of a pen tip for touch pen, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a reference view thereof showing a configuration of use.

The broken lines in FIG. 2 show portions of the pen tip for touch pen which form no part of the claimed design. The broken lines in FIG. 8 show environmental structure which form no part of the claimed design.
